CLAIM

The ornamental design for a controller with removable directional pad, as shown and described.

DESCRIPTION

FIG. 1 is a front perspective view of a controller with removable directional pad in a first configured state showing our new design;

FIG. 2 is a top view thereof;

FIG. 3 is a rear view thereof;

FIG. 4 is a front view thereof;

FIG. 5 is a left view thereof;

FIG. 6 is a right view thereof;

FIG. 7 is an exploded front perspective view of a controller with removable directional pad, shown in a second unconfigured state;

FIG. 8 is an exploded top view of FIG. 7;

FIG. 9 is an exploded rear view of FIG. 7;

FIG. 10 is an exploded front view of FIG. 7;

FIG. 11 is an exploded left side view of FIG. 7;

FIG. 12 is an exploded right side view of FIG. 7; and,

FIG. 13 is an exploded bottom view of FIG. 7.

The broken line showing of the various unshaded elements of the controller with removable directional pad in FIGS. 1–13 is for environmental purposes only and forms no part of the claimed design.
